UNITED STATES PATENT OFFICE.

JAMES H. ROBERTS, OF CHARLESTON, SOUTH CAROLINA.

GEOMETRICAL TOOL.

1,393,970.

Specification of Letters Patent.

Patented Oct. 18, 1921.

Application filed January 3, 1921. Serial No. 434,613.

To all whom it may concern:

Be it known that I, JAMES H. ROBERTS, a citizen of the United States, residing at Charleston, in the county of Charleston and 5 State of South Carolina, have invented a new and useful Geometrical Tool, of which the following is a specification.

This invention relates to a geometrical tool of the same general type as that disclosed in Patent No. 1,243,343 issued to me on Oct. 16, 1917, one of its objects being to provide a tool of this character having all 10 of the advantages present in the patented device but which does not require the use 15 of a graduated segment extending through more than 90°.

A further object is to provide a tool of this character utilizing adjustable graduated blades or arms which are normally disposed 20 at right angles to each other and which are adjustable angularly as one body relative to the main or stationary arm of the tool, one 25 of the movable arms having an index readable in connection with the graduations on the segment.

A still further object is to so mount the movable arms that they may be folded together so as to lie longitudinally upon the main or stationary arm when the tool is not 30 in use, thus to be easily stored in a box or carried in a pocket.

Another object is to provide a tool in which the movable arms can be quickly and securely held at right angles to each other.

35 Another object is to provide a stop for limiting the movement of the movable arms when one of them is brought to position at right angles to the main or stationary arm.

With the foregoing and other objects in 40 view which will appear as the description proceeds, the invention resides in the combination and arrangement of parts and in the details of construction hereinafter described and claimed, it being understood 45 that, within the scope of what is claimed, changes in the precise embodiment of the invention shown can be made without departing from the spirit of the invention.

In the accompanying drawings the preferred form of the invention has been shown.

In said drawings—

Figure 1 is a plan view of a portion of the tool with the parts set up for use.

Fig. 2 is a similar view showing the tool 55 folded.

Fig. 3 is an edge view, a portion being shown in section.

Referring to the figures by characters of reference 1 designates the stationary or main arm of the tool which can be of any 60 desired length and has two straight parallel edges adjacent which are provided graduations designating inches or any other units of measure, and fractions thereof. Secured on this arm 1 preferably near one end thereof is a segment 2 one end of which is extended slightly beyond one side edge of the arm 1 and has an inwardly extending ear 3 which laps and is secured to the arm 1, the other end of the segment being fastened directly 70 to the arm. Formed on the segment 2 are two series of graduations extending through 90°, the graduations of one series being indicated by numerals ranging from "0" to "90" and the graduations of the other series 75 being indicated by numerals ranging from "90" to "180", the "90" graduations of the two series coinciding and the "0" and "180" graduations likewise coinciding as will be apparent by referring to the drawings. 80

A combined pivot and binding screw 4 is threaded in the arm 1, the segment 2 being concentric therewith, and pivotally mounted on this screw is a movable arm 5 suitably graduated and one end of which abuts 85 against and is slidable along the inner arcuate edge of the segment 2. This end has an indicating graduation 7 or the like designed to register with any one of the graduations on the segment so that the angle at which 90 the arm 5 is extended relative to the arm 1 can thus be determined readily.

The parts are so proportioned that when the graduation 7 alines with the graduation designated by the numeral "90", the arm 5 95 abuts against the ear 3 which thus acts as a stop.

Pivots mounted on the screw 4 is another movable arm 8 suitably graduated and which has a lug 9 upstanding therefrom 100 adapted to be detachably engaged by one end of a link 10 the other end of which is pivotally attached to the arm 5 as shown at 11. When the link 10 is in engagement with the lug 9, as shown in Fig. 1, the two 105 arms 5 and 8 are held at right angles to each other and when the arm 5 is adjusted angularly to a desired position relative to the segment the arm 8 will likewise move therewith, thus giving at all times a line at 110

right angles to that which might be scribed along the arm 5 and which forms with the edge of the arm 1 an angle which, when added to that formed between the arms 1 5 and 5 will equal a right angle.

When the tool is not in use the link 10 can be sprung out of engagement with the lug 9 and the arms 5 and 8 swung together so as to lie parallel with each other and with 10 the arm 1 as shown in Fig. 2.

This tool can be used for all of the purposes for which any tool of a similar character can be used, such as laying off the end cuts of rafters, laying out braces, stair horses, 15 etc., as will be apparent to those skilled in the art.

What is claimed is:—

1. A geometrical tool comprising a main arm, a graduated segment secured thereon 20 and having an end stop, pivotally connected arms mounted for angular adjustments upon the main arm, one end of one of said connected arms abutting against and being movable along the under edge of the segment and against the stop, and a brace outside of the working angle formed by the arms for holding the pivotally connected arms normally at a predetermined angle to each other.
2. A geometrical tool including a main arm, a graduated segment mounted thereon, 30 movable arms, means for pivotally connect-

ing said arms together and to the main arm and for holding them against relative movement, one of the movable arms abutting 35 against and being shiftable along the inner edge of the segment and carrying an index, and means extending between the pivot of the arms and the segment for maintaining the movable arms at a predetermined 40 angle relative to each other during the movement thereof relative to the main arm, said means being shiftable to permit folding of the movable arms.

3. A geometrical tool including a main 45 arm, a segment extending over one face thereof and having a terminal stop, superposed movable arms, a combined pivot and clamping screw engaging all of the arms, one of said arms being movable along one 50 edge of the segment and against the stop and the other movable arm being movable across the segment and past the stop, and a brace carried by one of the movable arms and detachably engaging the other movable 55 arm for holding said arms normally at right angles to each other.

In testimony that I claim the foregoing as my own, I have hereto affixed my signature in the presence of two witnesses.

JAMES H. ROBERTS.
